BOTTLE

John Le Roy Parcels, Bordentown, N.J.

Filed Nov. 19, 1965, Ser. No. 88,157

Term of patent 14 years

(Cl. D58—6)

FIG. 1

I claim:

The ornamental design for a bottle, substantially as shown.
